(57) **CLAIM**

The ornamental design for storage rack, as shown and described.

DESCRIPTION

FIG. 1 is a top perspective view of a storage rack design showing my new design ;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

Any shading and cross-hatching are not features of the design but are utilized to illustrate the surface contours of the storage rack design in the drawings.

1 Claim, 8 Drawing Sheets

FIG. 1
